UNITED STATES PATENT OFFICE

168,754

SPACE HEATER

Willis N. Nelson, Wisconsin Rapids, Wis., assignor
to Prentiss Wabers Products Co., Wisconsin
Rapids, Wis., a corporation of Wisconsin

Application January 15, 1952, Serial No. 18,069

Term of patent 14 years

(Cl. D81—19)

To all whom it may concern:

Be it known that I, Willis N. Nelson, a citizen
of the United States, residing at Wisconsin
Rapids, in the county of Wood and State of Wisconsin,
have invented a new, original, and ornamental
Design for Space Heaters, of which the
following is a specification, reference being had
to the accompanying drawing, forming part
thereof, wherein—

Figure 1 is a perspective view looking down and
toward the front of a space heater, showing my
new design;

Fig. 2 is a perspective view looking toward the
front and one side thereof;

Fig. 3 is a perspective view looking toward the
space heater side opposite that which is shown
in Fig. 2; and

Fig. 4 is a perspective view looking toward the
rear side thereof.

I claim:

The ornamental design for a space heater, as
shown.

WILLIS N. NELSON.
